(57) **CLAIM**

The ornamental design for a pendant light, as shown and described.

DESCRIPTION

FIG. 1 is a front view of a pendant light illustrating our new design;

FIG. 2 is a left side view thereof;

FIG. 3 is a right side view thereof;

FIG. 4 is a bottom view thereof; and,

FIG. 5 is a side perspective view of a pendant light illustrating our new design.

The broken lines immediately adjacent to the claim depict the bounds of the claimed design, while all other broken lines are directed to environment. The broken lines form no part of the claimed design.

1 Claim, 5 Drawing Sheets
